William W. Coleman Inventor,
By his Attorneys,

UNITED STATES PATENT OFFICE.

WILLIAM W. COLEMAN, OF POTSDAM, NEW YORK.

DESIGN FOR A SHADE-ROLLER BRACKET.

SPECIFICATION forming part of Design No. 32,640, dated May 8, 1900.

Application filed April 7, 1900. Serial No. 12,027. Term of patent 7 years.

To all whom it may concern:

Be it known that I, WILLIAM W. COLEMAN, a citizen of the United States, residing at Potsdam, in the county of St. Lawrence and State of New York, have invented and produced a new and useful original Design for Shade-Roller Brackets, of which the following is a specification.

This invention relates to a new and original design for a shade-roller bracket, and has for its object to provide a design of this character which shall be both useful and ornamental.

The leading feature of the present design resides in the straight rod-like body having the opposite terminal substantially U-shaped loops at the respective ends of the body, said loops being in the same plane and extending at the same side of the body, and an outwardly-directed straight projection extending from the outer end of one of the loops and axially with respect to the body.

Minor features of the design reside in the pointed end of the projection, the screw threads which extend for the greater length thereof, and in the outwardly-bowed shape of the outer side of the opposite U-shaped loop, said side also extending beyond the opposite side of the body portion.

In the drawings, Figure 1 is a perspective view of a shade-roller bracket embodying the herein-described design. Fig. 2 is a side elevation thereof.

Corresponding parts in the figures of the drawings are designated by like characters of reference.

Referring to the accompanying drawings, 1 designates the body of the bracket, which is in the form of a straight rod, having at its opposite ends the terminal substantially U-shaped loops 2 and 3, respectively, which are located in the same plane, extend entirely at one and the same side of the body, and are of substantially-equal lengths. At the outer end of the outer side of the loop 3 is an outwardly-directed and substantially-straight projection 4, which is disposed axially with respect to the body 1, has a pointed extremity 5, and is screw-threaded for the greater part of its length. The opposite loop 2 has the outer side thereof bowed outwardly and extended transversely across the adjacent end of the body and projects at the opposite side thereof.

What is claimed is—

The design for a shade-roller bracket, herein shown and described.

In testimony that I claim the foregoing as my own I have hereto affixed my signature in the presence of two witnesses.

WILLIAM W. COLEMAN.
